No. 37,156.

Patented October 4, 1904.

UNITED STATES PATENT OFFICE.

GEORGE H. RHYNEDANCE, OF NEW HAVEN, CONNECTICUT, ASSIGNOR TO
NEW HAVEN CLOCK CO., OF NEW HAVEN, CONNECTICUT, A CORPO-
RATION.

DESIGN FOR A CLOCK-CASE.

SPECIFICATION forming part of Design No. 37,156, dated October 4, 1904.

Application filed September 9, 1904. Serial No. 223,927. Term of patent $\frac{1}{2}$ years.

To all whom it may concern:

Be it known that I, GEORGE H. RHYNEDANCE, a citizen of the United States, residing at New Haven, in the county of New Haven and State of Connecticut, have invented a new, original, and ornamental Design for a Clock-Case; and I do hereby declare the accompanying drawing to be a full, clear, and exact illustration of the same, and which said drawing constitutes part of this specification and represents a per-

spective view of a clock-case embodying my design.

I claim—

The ornamental design for a clock-case as shown.

GEORGE H. RHYNEDANCE.
